(57) **CLAIM**

The ornamental design for a front bumper for automobile as shown and described.

DESCRIPTION

FIG. 1 is a front and left perspective view of a front bumper for automobile, showing our new design;

FIG. 2 is a rear and right perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The portions of the front bumper for automobile surrounded by broken lines and shown in half-tone shading form no part of the claimed design.
